UNITED STATES PATENT OFFICE

146,861

DESIGN FOR A COMBINED INFANT WARD- ROBE AND BATH UNIT

Lena B. Kneeland, Kenmore, N. Y.

Application July 27, 1945, Serial No. 121,013

Term of patent 14 years

(Cl. D4—4)

To all whom it may concern:

Be it known that I, Lena B. Kneeland, a citizen of the United States, residing at Kenmore, in the county of Erie and State of New York, have invented a new, original, and ornamental Design for a Combined Infant Wardrobe and Bath Unit, of which the following is a specification, reference being had to the accompanying drawing, forming part thereof.

Fig. 1 is a perspective view of a combined infant wardrobe and bath unit of my new design in closed condition;

Fig. 2 is a rear elevation thereof;

Fig. 3 is a perspective view similar to Fig. 1, but showing the unit in opened condition; and

Fig. 4 is a front view thereof.

I claim:

The ornamental design for a combined infant wardrobe and bath unit, as shown.

LENA B. KNEELAND.
